MOP

Raymond C. Tillinghast, Memphis, Tenn., assignor to
Gem, Incorporated, Byhalia, Miss., a corporation of
Mississippi

Filed Mar. 19, 1965, Ser. No. 84,356

Term of patent 14 years

(Cl. D9—2)

FIG. 1 is a perspective view of a mop, showing my new design.

FIGURE 2 is a side elevational view thereof.

FIGURE 3 is a top plan view.

FIGURE 4 is a front elevational view.

FIGURE 5 is a rear elevational view.

FIGURE 6 is a bottom plan view.

The side not shown is a mirror image of the side illustrated in FIGURE 2.

The dominant features of my design reside in the portions shown in full lines, the fragmentary showing of the handle being for illustrative purposes only.

I claim:

The ornamental design for a mop, as shown and described.
